JOHN E. ALEXANDER, OF COVINGTON, VIRGINIA, ASSIGNOR OF ONE-HALF
TO IRA DEW, OF COVINGTON, VIRGINIA.

RAIL-JOINT.

No. 805,831.

Specification of Letters Patent.

Patented Nov. 28, 1905.

Application filed June 22, 1905. Serial No. 266,427.

To all whom it may concern:

Be it known that I, JOHN E. ALEXANDER, a citizen of the United States, and a resident of Covington, in the county of Alleghany and State of Virginia, have made certain new and useful Improvements in Rail-Joints, of which the following is a specification.

My invention is an improvement in rail-joints; and it consists in certain novel constructions and combinations of parts, as will be hereinafter described and claimed.

In the drawings, Figure 1 is a perspective view of a rail-joint embodying my invention. Fig. 2 is a cross-section on about line 2 2 of Fig. 1. Fig. 3 is a detail perspective view of one end of the lug-carrying fish-plate. Fig. 4 is a detail side elevation of one end of one of the rails, and Fig. 5 is a detail view of one of the wedges.

The rails A may be of ordinary construction, except that I provide in their webs A' slots A², which are elongated in the direction of length of the rails and are adapted to receive the inwardly-projecting lugs B' on the fish-plate B. The fish-plates B and b are alike, except that the fish-plate b is not provided with the lugs B', but simply has bolt-holes formed through it to register with the bolt-holes b' formed through the fish-plate B and through the lugs B' on the inner side of said fish-plate, the bolts C passing through the openings in the fish-plates and being secured by nuts or otherwise, as desired. The formation of the holes b' for the bolts through the lugs B' of the fish-plate B is an important feature of the invention, as thereby all lateral or shearing strain on the bolts is prevented.

At their lower ends on their outer faces the fish-plates B and b are provided with the inwardly-tapering surfaces B³ and b³ and the rail ends fit at their bases in the chair D, which is of a special construction, as will be described. This chair has the base-plate D' and is provided at the opposite edges thereof with the inwardly-projecting clasp portions D², whose inner edges slope both vertically and longitudinally, being undercut vertically at d and tapering longitudinally at d' from a point midway between their ends outwardly toward their opposite ends and preferably corrugated on their inner edges, as shown, to coöperate with corrugations e on

the outer edges of the clamping-keys E, as best shown in Fig. 1 of the drawings.

In operation the fish-plates are applied as shown in Figs. 1 and 2, the rail ends being seated in the chair, and the keys are then driven between the inner edges of the clasp-plates D² of the chair and the undercut lower edges of the fish-plates, and such keys when they are driven home operate to press the inner edges of the fish-plates inwardly toward the rails and to bind the upper edges of the fish-plates snugly against the tread portions of the rails and to clamp the rails securely within the chair, as described. These keys taper longitudinally on their outer edges at E' and also slope transversely on said edges to coöperate with the undercut edges d of the chair, and by the corrugated edges of the keys interlocking with the corresponding edges of the chair the keys as they are pressed home are locked against accidental retrograde movement. In practice I prefer to make the fish-plates of such height that a slight space will be left between their lower edges and the webs of the rails to permit the keys to bind the fish-plates in place when the said keys are driven home in the use of the invention.

The construction is simple, inexpensive, and furnishes a strong easily-applied joint, as will be understood from the drawings and foregoing description.

Having thus described my invention, what I claim as new, and desire to secure by Letters Patent, is—

1. The rail-joint herein described comprising the rails having their webs provided with slots elongated in the direction of length of the rails, and fish-plates having bolt-openings and one of said plates being provided on its inner side with inwardly-projecting lugs to fit in the slots of the rails and having its bolt-holes formed through said lugs, the fish-plates being provided on their outer faces at their lower edges with inwardly-tapering surfaces, the chair provided at its edges with inwardly-projecting clasp portions overlying the base of the rails and having their inner edges tapered outwardly from a middle point toward their ends, said inner faces being also corrugated and tapering outwardly from their upper to their lower edges, the bolts passing through the fish-plates and rail-sec-

tions, and the keys tapering longitudinally and transversely and corrugated on their outer edges to interlock with the corrugations of the clasp portions of the chair when driven and operating between said clasp portions and the inwardly-sloping surfaces at the lower edges of the fish-plates, substantially as set forth.

2. The combination of the chair, the rail-sections having their webs provided with slotted openings, the fish-plates, one of which is provided with lugs fitting said slotted openings and having bolt-holes formed through said lugs and the opposite fish-plate, the bolts passing through said holes, and the keys operating between the chair and the fish-plates, substantially as set forth.

3. In a rail-joint the combination of the rail-sections, the chair provided at its ends with clasp portions overlying the base of the rail-sections and tapering on their inner edges from their middles outwardly toward their ends and undercut on their inner edges, the fish-plates and the keys operating between the tapered undercut edges of the chair and the said fish-plates, substantially as set forth.

4. The combination in a rail-joint with the rail-sections having slotted openings, of the fish-plates, one of which is provided with in-

wardly-projecting lugs entering the slots in 30 the fish-plates and with bolt-holes through said lugs, the opposite fish-plate having openings coinciding with those in the lugs and the bolts passing through said openings, substantially as set forth. 35

5. The combination of the rail-sections, the fish-plates provided on their outer sides at their lower ends with the undercut surfaces, the chair receiving the rail-sections and provided at its edges with the clasp portions 40 overlying the base of the rails and tapering on their inner edges from their middles toward their ends, and the keys operating between said surfaces of the chair-clasps and the undercut surfaces of the fish-plates, substantially as set forth. 45

6. The combination of the rails, the fish-plates, the chair receiving the rails and having clasp portions overlying the base of the rails and corrugated on their inner edges, and the keys operating between the fish-plates and the corrugated edges and formed to co-operate with the latter, substantially as set forth. 50
